UNITED STATES PATENT OFFICE.

FRANK J. HAYWARD, OF SPENCER, WISCONSIN.

SNOW-PLOW.

1,021,928.

Specification of Letters Patent.

Patented Apr. 2, 1912.

Application filed November 15, 1910. Serial No. 592,437.

To all whom it may concern:

Be it known that I, FRANK J. HAYWARD, a citizen of the United States, residing at Spencer, in the county of Marathon and State of Wisconsin, have invented certain new and useful Improvements in Snow-Plows; and I do hereby declare the following to be a full, clear, and exact description of the invention, such as will enable others skilled in the art to which it appertains to make and use the same.

My invention relates to new and useful improvements in snow plows and more particularly to that class adapted to be used for the removing of snow from trackways and one of my objects is to provide a frame for the plow and mount the same upon wheels.

A further object is to provide a mold board or plow for moving the snow to the edges of the trackway and additional means for moving the snow out of the path of the flanges of the wheels.

A further object is to provide a tongue by means of which the snow plow may be propelled, one end of the tongue having means for adjustably attaching the tongue to the draw head of an engine and

A further object is to provide wings and pivotally secure the same at the edges of the mold board, said wings having means attached thereto for moving the free ends thereof inwardly or outwardly.

Other objects and advantages will be hereinafter set forth and pointed out in the specification.

In the accompanying drawings, which are made a part of this application, Figure 1 is a top plan view of the snow plow complete, showing the coupling for attaching the same to the draw head of an engine. Fig.

2 is a sectional view as seen on line 2—2, Fig. 1. Figs. 3 and 4 are detail plan views of the ends of the bars employed for moving the wings inwardly or outwardly, and

Fig. 5 is a plan view of one of the pinions to coöperate with the racks on said bars. Fig. 6 is a sectional view as seen on line 6—6 of Fig. 1.

Referring to the drawings in which similar reference numerals designate corresponding parts throughout the several views, 1 indicates the frame of my improved plow, which is mounted upon an axle 2, the opposite ends of said axle 2 being received in the bearing 2¹ carried by the side beams 1¹ of the frame 1, the axle 2 having

wheels 3 rigidly secured thereon which are adapted to travel upon the track 4.

Attached to the forward portion of the frame 1 is a mold board 5, which inclines from front to rear and also extends at an angle laterally so that the snow when coming in contact therewith will travel outwardly to a point beyond the track rails. Secured to the portion 1^a of the frame work 60 below the mold board are sockets 6, in which are slidably mounted plates 7, which plates are adapted to be lowered to a point below the lower edge of the mold board and are positioned sufficiently near the inner faces 65 of the track rails as to remove the snow, etc., adjacent the track rails, thereby obviating any possibility of the snow backing between the track rails and the flanges of the wheels. The plates are raised and lowered through 70 the medium of a lever 8, which is pivotally mounted on the frame 1 and has the usual form of latch 9, which coöperates with a segmental rack 10 and by means of which the plates may be extended below the mold 75 board at varying distances. The frame 1 has attached thereto in any preferred manner a rearwardly extending tongue 11, the free end of which is provided with a threaded sleeve 12, which sleeve is pivotally secured to the end of the tongue. Coöperating with the sleeve 12 is a threaded bolt 13, the ends of which extend through the arms 80 of a yoke 14, said yoke being adapted to be pivotally secured to the draw head of an engine or other parts of a train. The sleeve 12 is of less length than the distance between the arms of the yoke so that by turning the bolt 13 the edge of the mold board 85 may be adjusted toward or from the track 90 rails.

Hingedly secured at the rear side edges of the mold board 5 are wings 15, which are adapted to be swung outwardly to increase the path made by the plow through the snow and the outward swinging movement of said wings is controlled by means of thrust bars 16 and 17, which are pivotally connected at their ends to the inner faces of the wings, while the inner ends thereof 100 overlap each other and project through a housing 18 carried by the tongue 11. The overlapping ends of the bars are provided with elongated slots 19 and 20, respectively, one inner face of each slot having teeth 21 105 and 22, respectively, the teeth of the bar 16 being at one side of the slot, while the teeth

of the bar 17 are parallel with and opposite the teeth of the bar 16.

Extending transversely through the tongue 11 and the housing 18 is a crank shaft 23 and on that portion of the shaft extending through the housing are placed gears 24 and 25, which coöperate respectively with the teeth 21 and 22 of the thrust bars, and in view of the fact that said teeth are opposed to each other, the bars will be simultaneously moved inwardly or outwardly when the shaft is rotated. The upper end of the shaft terminates in a crank 26 by means of which the shaft and gears thereon may be rotated and in order to prevent reverse rotation of the shaft, except when so desired, a ratchet 27 is attached to the shaft and coöperating therewith is a latch 28 mounted on the tongue 11, and it will be readily seen that as long as the latch is in engagement with the ratchet the shaft will be held against rotation in one direction, thus holding the thrust bars in their extended positions. When the wings are extended, should for any reason the plow be moved rearwardly, the latch 28 is manually released from the ratchet 27 and the shaft 23 rotated to swing the wings inwardly, thereby obviating any possibility of the wings gathering any snow and moving it back on the track.

This device can be readily attached to a train and in view of the pivotal connection of the tongue with the sleeve and the draw head, the plow will readily travel around curves or over uneven places in the track-way, without affecting the action of the plow. It will likewise be seen that the plow can be quickly disconnected from the draw head and removed to a side track or other position when there is no further use for the same, that the path made by the plow may be readily increased by swinging the wings outwardly as described and that the end of the tongue may be readily adjusted to adjust the lower edge of the mold board with respect to the track way.

What I claim is:

1. A snow plow, comprising the combination with a frame, an axle and supporting wheels therefor, of a mold board carried by the frame, wings hingedly secured at the

rear side edges of the mold board, means to swing said wings inwardly or outwardly, a tongue attached to the frame, means for attaching the rear end of the tongue to a propelling means and means for adjusting the rear end of the tongue upwardly or downwardly. 55

2. In a snow plow the combination with 60 a frame, supporting wheels therefor, a mold board attached to said frame and a propelling tongue, of wings hinged at one end to the frame at the rear side edges of the mold board, thrust bars pivoted to the wings, a 65 housing carried by the tongue through which the inner ends of the thrust bars extend, the overlapping ends of the thrust bars having slots, teeth along one edge of each slot, the teeth of one slot being opposed to the teeth of the other slot, gears coöperating with 70 said teeth, a shaft carrying said gears and a crank by means of which said shaft may be rotated.

3. In a snow plow the combination with 75 a frame, supporting wheels therefor, a mold board carried by the frame, a tongue attached at one end to the frame, a threaded sleeve pivoted to the opposite end of the tongue, a yoke by means of which the tongue 80 may be attached to a propelling means and a threaded bolt carried by the yoke and extending through said sleeve for adjusting the tongue upwardly or downwardly.

4. In a snow plow the combination with 85 a frame and supporting wheels therefor, of a mold board attached to the frame, of wings hinged to the frame and the edge of the mold board, thrust bars attached to said wings, means engaging the inner ends of 90 the thrust bars to move the same endwise, a tongue attached to the frame, sockets secured on the under side of said frame, plates slidably mounted in said sockets and a lever positioned upon said tongue for adjusting 95 said plates.

In testimony whereof I have signed my name to this specification in the presence of two subscribing witnesses.

FRANK J. HAYWARD.
